UNITED STATES PATENT OFFICE.

BERT W. PUNCHES, OF PLYMOUTH, MICHIGAN.

AIR GUN.

Application filed February 6, 1922. Serial No. 534,320.

To all whom it may concern:

Be it known that I, BERT W. PUNCHES, a citizen of the United States of America, residing at Plymouth, in the county of Wayne 5 and State of Michigan, have invented certain new and useful Improvements in Air Guns, of which the following is a specification, reference being had therein to the accompanying drawings.

10 The invention relates to air guns and has for its object the provision of a simple construction of gun which may be manufactured at a relatively low cost and which is efficient in operation. Other objects of the invention 15 are to provide a gun in which the true barrel is secured to the plunger and has an aperture near its inner end for the passage of air compressed by the movement of the plunger toward the abutment; to provide 20 means within the true barrel for holding the projectile to its seat in the true barrel, which means permits of the insertion of the projectile when the true barrel is in loading position; to provide a guide within the false 25 barrel for the forward end of the true barrel which is adapted to receive a projectile other than the ordinary projectile insertable within the true barrel; to make this guide longitudinally adjustable relative to the true 30 barrel to permit of the insertion of the projectiles passing through the guide into the magazine space between the false and true barrels; and to provide an inclined annular deflector within the false barrel and 35 rounding the true barrel for guiding the projectiles within the magazine space to the aperture in the true barrel, when in loading position.

With these objects in view, the invention 40 resides in the novel features of construction and combinations and arrangements of parts as more fully hereinafter set forth.

In the drawings:

Figure 1 is a horizontal section partly in 45 plan through a portion of an air gun embodying my invention and showing the plunger in retracted position;

Figure 2 is a similar view showing the plunger in its forward position of travel;

50 Figure 3 is a cross section taken at right angles to Figure 1;

Figure 4 is a cross section partly in elevation taken at right angles to Figure 2;

55 Figure 5 is a perspective view of the forward end of the gun showing the guide for the true barrel.

Fig. 6 is a fragmentary section of some parts shown in Fig. 3 on an enlarged scale.

1 is the false barrel of the air gun, 2 the true barrel arranged substantially concentrically therewithin, 3 the plunger slidable within the false barrel and 4 the coil spring for forcing the plunger forward from its retracted position toward the abutment 5 secured within the false barrel and surrounding the true barrel.

60 The true barrel 2 is fixedly secured to the plunger 3 and slidably engages the abutment 5 as well as the guide 6 within the forward end of the false barrel. In the present instance, the true barrel is secured to the plunger by means of the reduced end of the plunger stem 7 threadedly engaging the rear end of the true barrel. The plunger head 8 is clamped against the shoulder 9 70 formed upon the stem by means of the struck out lugs 10 of the true barrel, the arrangement being such that the openings 11 formed by striking out the lugs permit of the passage of the air compressed between the 75 plunger head 8 and the abutment 5 into the true barrel to eject the projectile 12 within the true barrel. The true barrel has the projectile aperture 13 formed in its upper side and located forward of the side openings 11, this aperture being so located that when the plunger head is in engagement with or adjacent to the abutment, it will be located in advance of the abutment as shown 80 particularly in Figures 2 and 4 so that a new projectile may be allowed to pass through the aperture into the true barrel. The true barrel also has an annular shoulder 14 in advance of the projectile aperture 13, the diameter of this shoulder being such 85 that the projectile will have a good sliding fit therewith, and form an air tight seal.

90 To hold the projectile in frictional engagement with this very slight annular shoulder, there is the coil spring 15 within the rear 100 end of the true barrel and having its rear end abut the forward end of the plunger stem, and its farthest advanced portion abut the projectile. However, to retract the farthest advanced portion of this coil spring 105 to clear the aperture 13 when in loading position, the coil spring has the straight portion extending rearwardly through the convolutions from the farthest advanced portion and a transversely extending end portion 16 which passes through one of the side apertures 11 so that it will engage the rear 110

face of the abutment 5 when the plunger head is in its forward position of adjustment so that as a consequence, the coil spring is compressed and its farthest advanced portion does not extend beyond the front face of the abutment when the true barrel is in loading position. As soon as the plunger has been retracted sufficiently to permit the coil spring to expand, the latter yieldably 10 forces the projectile into frictional engagement with its seat.

With the construction as thus far described and with the parts in the positions shown in Figure 2, the projectile aperture 13 is located in advance of the abutment 5 and the farthest advanced portion of the coil spring 15 is retracted to uncover this aperture so that a projectile within the space between the true and false barrels and in advance of the abutment may enter the aperture. Then upon retracting the plunger with the true barrel, the coil spring 15 is permitted to expand so that its farthest advanced portion engages the projectile and yieldably forces it into frictional engagement with the restricted portion of the true barrel to form an air tight seal. In the retracted position of the plunger as shown in Figure 1, the coil spring 4 is compressed so that upon release of the trigger mechanism of the gun, this coil spring forces the plunger forward, which compresses the air trapped in the space between the false and true barrels and the abutment and plunger 25 head until the pressure of this air is sufficient to eject the projectile from the true barrel, this air entering the true barrel through the side apertures and projectile aperture of the true barrel near its rear end. As the plunger comes into proximity to the abutment, the projectile seating coil spring is compressed and its farthest advanced end is retracted to permit of the insertion of the next projectile 40 into the true barrel.

The space 17 between the false barrel 1 and true barrel 2 and in advance of the abutment 5, is the magazine of the gun, and in order to load this magazine with the projectiles, the guide 6 for the forward end of the true barrel is longitudinally adjustable relative to both the false and true barrels. This guide has at its rear end and in its lower side, an opening 18 which is covered at all times by the true barrel when the guide is in its normal position. To uncover this opening, the plunger and true barrel are drawn back to retracted position, and the guide is then advanced to its forward position as indicated by the dotted lines, at 50 which time the aperture is in advance of the forward end of the true barrel so that projectiles inserted into the guide may pass through the aperture and into the magazine of the gun. The upper end wall of the 55 false barrel 1 has the L-shaped slot 19 which

is engaged in by a pin 20 upon the guide, this pin in the normal position of the guide constituting the forward gun sight. To hold the pin in the portion of the slot extending transversely of the gun, there is the flat 70 spring 21 secured at its forward end to the false barrel and at its rear end to the downwardly extending flange 22 of the guide. This spring, however, permits of rotation of the guide relative to the false barrel and 75 then of longitudinal outward movement of the guide relative to the false barrel to effect the loading of the magazine.

To obstruct the forward end of the true barrel 2 when the guide 6 is positioned relative to the true barrel to effect the loading of the magazine, there is the spring 23 upon the upper inner wall of the guide which will extend across the forward end of the true barrel when the guide has been advanced to a position to load the magazine.

To direct the projectiles within the magazine 17 to the projectile aperture 13 when the true barrel is in loading position, there is the annular deflector 24 within the false barrel and surrounding the true barrel, this deflector being upwardly and rearwardly inclined and having an opening 25 in its portion above the true barrel which registers with the trough 26, the rear end of the trough terminating just in advance of the projectile aperture and thereabove. The trough is carried by this inclined deflector.

This gun is adapted for use with other projectiles such as arrows, etc., these projectiles being adapted to be inserted within the guide 6, and to abut the forward end of the true barrel in retracted position if desired. They also may be formed with plungers insertable within the true barrel to thereby secure a stronger impetus from the air compressed by the forward movement of the plunger.

To produce a rotation of these projectiles during their flight, the guide has the spiral groove 27 in its inner wall which may be engaged in by a lateral projection or lug upon these projectiles.

What I claim as my invention is:

1. In an air gun, the combination with a compression chamber, of a plunger slideable therewithin, and a true barrel secured to said plunger and provided with apertures near its inner end upon diametrically opposite sides thereof for the passage of air compressed in said chamber.

2. In an air gun, the combination with a compression chamber, of a plunger slideable therewithin, and a true barrel secured to said plunger and provided with an aperture near its inner end for the passage of the air compressed in said chamber and a second aperture for the insertion of the projectile into the true barrel.

3. In an air gun, the combination with a

- compression chamber having an abutment, of a plunger slidable within said chamber and movable toward said plunger to compress air, a true barrel slidably engaging said abutment and secured to said plunger, said true barrel being provided with an aperture near its inner end adapted for the passage of compressed air on one side of said abutment and having a second aperture 5 adapted for the insertion of a projectile into said true barrel on the other side of said abutment, and means within said true barrel and adapted to engage the projectile after its insertion for holding said projectile in a predetermined position. 10
4. In an air gun, the combination with a compression chamber having an abutment, of a plunger slidable within said chamber and movable toward said abutment, a true 15 barrel slidably engaging said abutment and secured to said plunger, said true barrel being provided with an aperture for the passage of compressed air and a second passage for the insertion of a projectile thereinto, said 20 true barrel also being provided with a seat for the projectile beyond the first mentioned aperture, and a longitudinally movable yieldable member permitting of the insertion of said projectile into said true barrel, but being adapted to engage said projectile to force the same to its seat upon movement of the plunger away from said abutment. 25
5. In an air gun, the combination with a plunger comprising a stem having a shoulder at its outer end, and a head clamped against said shoulder, of a true barrel secured to said stem and having a struck out lug for clamping said head against said shoulder. 30
6. In an air gun, the combination with a compression chamber having an abutment, of a plunger slidable within said chamber comprising a stem having a shoulder at its outer end, and a head clamped against said shoulder, and a true barrel slidably engaging said abutment and secured to said stem, said true barrel having a struck out lug near its inner end for clamping said head against said shoulder, the aperture formed by 35 stamping out said lug constituting a passage for air compressed in said chamber into said true barrel. 40
7. In an air gun, the combination with a false barrel and a true barrel, of a member within said false barrel for positioning the forward end of said true barrel, said member being provided with an aperture normally closed by said true barrel but adapted to be exposed beyond the end of said true barrel for the insertion of a projectile through said member and into the space between said false and true barrels. 45
8. In an air gun, the combination with a false barrel and a true barrel longitudinally slidably mounted therewithin, of 50 a guide for the forward end of said true barrel, said guide being movable longitudinally relative to said false and true barrels and having an aperture normally closed by said true barrel but adapted to be exposed upon adjustment of said guide whereby a projectile may be inserted through said guide and into the space between said false and true barrels. 55
9. In an air gun, the combination with a false barrel and a true barrel, a member within said false barrel for positioning the outer end of said true barrel, said member having an aperture therein normally covered by said true barrel, but adapted to be exposed beyond the outer end thereof upon longitudinal movement of said member relative to said false and true barrels, and means upon said positioning member for obstructing the outer end of said true barrel to prevent the passage of a projectile thereinto from said positioning member. 60
10. In an air gun, the combination with a false barrel, of a true barrel longitudinally movable therewithin, a guide within the outer end of said false barrel for the outer end of said true barrel, said guide having an aperture normally covered by said true barrel but adapted to be exposed beyond its outer end, and said guide being rotatable relative to said false barrel as well as movable longitudinally thereof, to expose its aperture, and means connecting said false barrel and guide for normally holding said guide in a predetermined position relative to said false barrel. 65
11. In an air gun, the combination with a compression chamber, of a plunger slidably therewith, and a true barrel secured to said plunger and provided with an aperture near its inner end for the passage of the air compressed in said chamber and having a second aperture in advance of the aperture aforesaid, for the insertion of the projectile into the true barrel. 70
12. In an air gun, the combination with a compression chamber having an abutment, of a plunger slidable within said chamber and movable toward said abutment to compress air, a true barrel slidably engaging said abutment and secured to said plunger, said true barrel being provided with an aperture adapted for the passage of compressed air and having a second aperture adapted for the insertion of a projectile into said true barrel, and longitudinally movable means adapted to engage the projectile after its insertion for holding said projectile in a predetermined position. 75
13. In an air gun, the combination with a compression chamber having an abutment, of a plunger slidable within said chamber and movable toward said abutment to compress air, a true barrel slidably engaging said abutment and secured to said plunger, 80
14. In an air gun, the combination with a compression chamber having an abutment, of a plunger slidable within said chamber and movable toward said abutment to compress air, a true barrel slidably engaging said abutment and secured to said plunger, 85
15. In an air gun, the combination with a compression chamber having an abutment, of a plunger slidable within said chamber and movable toward said abutment to compress air, a true barrel slidably engaging said abutment and secured to said plunger, 90
16. In an air gun, the combination with a compression chamber having an abutment, of a plunger slidable within said chamber and movable toward said abutment to compress air, a true barrel slidably engaging said abutment and secured to said plunger, 95
17. In an air gun, the combination with a compression chamber having an abutment, of a plunger slidable within said chamber and movable toward said abutment to compress air, a true barrel slidably engaging said abutment and secured to said plunger, 100
18. In an air gun, the combination with a compression chamber having an abutment, of a plunger slidable within said chamber and movable toward said abutment to compress air, a true barrel slidably engaging said abutment and secured to said plunger, 105
19. In an air gun, the combination with a compression chamber having an abutment, of a plunger slidable within said chamber and movable toward said abutment to compress air, a true barrel slidably engaging said abutment and secured to said plunger, 110
20. In an air gun, the combination with a compression chamber having an abutment, of a plunger slidable within said chamber and movable toward said abutment to compress air, a true barrel slidably engaging said abutment and secured to said plunger, 115
21. In an air gun, the combination with a compression chamber having an abutment, of a plunger slidable within said chamber and movable toward said abutment to compress air, a true barrel slidably engaging said abutment and secured to said plunger, 120
22. In an air gun, the combination with a compression chamber having an abutment, of a plunger slidable within said chamber and movable toward said abutment to compress air, a true barrel slidably engaging said abutment and secured to said plunger, 125
23. In an air gun, the combination with a compression chamber having an abutment, of a plunger slidable within said chamber and movable toward said abutment to compress air, a true barrel slidably engaging said abutment and secured to said plunger, 130

said true barrel being provided with an aperture near its inner end adapted for the passage of compressed air, and having a second aperture adapted for the insertion 5 of a projectile into said true barrel, a yieldable member adapted to engage the projectile after its insertion for holding said projectile in a predetermined position, and means carried by said yieldable member 10 adapted to engage said abutment to compress said yieldable member in one position of said plunger.

14. In an air gun, the combination with a false barrel and a true barrel longitudinally slidably mounted therewithin, of a 15 guide for the forward end of said true barrel, said false barrel having a slot formed therein, and a pin carried by said guide and engaging said slot, said guide being movable relative to said false and true barrels, 20 said pin normally constituting a gun sight.

15. In an air gun, the combination with a false barrel and a true barrel longitudinally slidably mounted therewithin, of a 25 guide for the forward end of said true barrel, said false barrel having a slot formed therein provided with a transverse portion, a pin carried by said guide and engaging said slot, said guide being movable relative 30 to said false and true barrels, and spring means normally retaining said pin in engagement with the transverse portion of said slot.

16. In an air gun, the combination with 35 a compression chamber having an abutment,

of a plunger slidable within said chamber and movable toward said abutment to compress air, a true barrel slidably engaging said abutment and secured to said plunger, said true barrel being provided with an 40 aperture adapted for the passage of compressed air and having a second aperture adapted for the insertion of a projectile into said true barrel, an annular shoulder formed in said true barrel in advance of the 45 projectile aperture and longitudinally movable means adapted to engage the projectile after its insertion for holding the same in a predetermined position.

17. In an air gun, the combination with 50 a compression chamber having an abutment, of a plunger slidable within said chamber and movable toward said abutment to compress air, a true barrel slidably engaging said abutment and secured to said plunger, 55 said true barrel being provided with an aperture near its inner end adapted for the passage of compressed air and having a second aperture adapted for the insertion of a projectile into said true barrel, and a 60 yieldable member adapted to engage the projectile after its insertion for holding the same in a predetermined position, said yieldable member having a portion engageable with said abutment to compress said 65 yieldable member in one position of said plunger.

In testimony whereof I affix my signature.

BERT W. PUNCHES.
